[57] **CLAIM**

The ornamental design for a bed, as shown and described.

DESCRIPTION

FIG. 1 is a left front perspective view of a bed showing my new design;

FIG. 2 is a side view, the opposite side view being a mirror image thereof;

FIG. 3 is a front perspective view thereof;

FIG. 4 is a rear view of the footboard;

FIG. 5 is view of the canopy center; and,

FIG. 6 is a front elevational view of the bed without the canopy for convenience of illustration.

The broken lines are for environmental purposes only and form no part of the claimed design.
